AUTOMATIC STOPPING SYSTEM OF POWER LOOMS

Application filed April 23, 1928, Serial No. 272,338, and in Japan October 3, 1927.

This invention relates to improvements in an automatic stopping system of power looms comprising electrical means by which the loom stops its motion when a warp thread is broken or abnormally slackened.

A known electrical stopping mechanism consists of an electric magnet which controls the operating mechanism of stopping motion and a circuit for the electric magnet, which 10 circuit is closed when a dropper or wire-heald drops due to breaking of the corresponding warp thread.

In this invention the electric magnet for the operating mechanism of stopping motion is 15 not directly actuated by the circuit which comprises wire-healds, but it is actuated by the relay which in turn is actuated by the circuit comprising wire-healds.

Further in this invention a supplementary 20 circuit is provided in parallel with the circuit of wire-healds, and this new circuit is closed when the relay is once actuated by the circuit of wire-healds, so that the relay keeps its acting position although the main circuit of wire- 25 healds may be accidentally opened.

An object of this invention is to have the stopping mechanism start steadily and reliably by a weak electric current which passes through a wire-heald. A further object of 30 this invention is to minimize sparkling at a wire-heald which, while it is closing an electric circuit, may accidentally break the latter due to vibration of the loom causing 35 sparkling at the contact points.

In the accompanying drawing, Fig. 1 is 40 a diagrammatic view of the automatic stopping system for power looms according to this invention.

Fig. 2 is a side elevation of wire-healds 45 showing how a circuit is closed when a warp thread is broken.

Fig. 3 is a plan view of an operating mechanism stopping motion, taken on the line III-III in Fig. 1.

Figs. 4 and 5 are diagrammatic views of 50 two modifications according to this invention.

Fig. 1, 1 is a spring handle fixed to the 55 frame 2 of a power loom and extends upwards through a stepped slot in a handle-bracket 3

as in the usual case. A rocking lever 4 is pivoted at 4^a on the bracket, and a short pin 5 is horizontally and slidably held at its right end. This end always hangs downwards due to unbalanced weight, but is raised 55 upwards when its lift end in the form of a flat iron piece 4^b is pulled by an electric magnet C₂, so that the horizontal pin occupies a position before the spring handle and in the way of a projection 6 provided on the slay 60 7 of the loom.

Two contact pieces 8 and 9 are fixed beneath the handle-bracket electrically insulated from one another, between which a switching knife 10 on the spring handle is 65 inserted while the loom is running.

A relay comprising an electric magnet C₁, a spring iron piece 11 with a switching knife 12 and two contact pieces 13 and 14 are provided at a proper position on the frame, and 70 the main electric circuit for the magnet C₁ consists of the lines 15, 17, the contacting pieces 9, 10 and 8, line 18, batteries B₁, and the line 16, wire-healds being inserted between the lines 15 and 16 as shown in Figs. 75 2 and 3.

The circuit for the magnet C₂ consists of the line 19, the contact pieces 13 and 12, spring iron piece 11, line 20, the batteries B₁, the line 18, the contact pieces 8, 10 and 9, and the line 80 21 so that if the spring iron piece 11 is not pulled by the magnet C₁ to close the space between the pieces 13 and 14, this circuit is not closed and the magnet C₂ is not energized.

When the contact pieces 13 and 14 are 85 electrically connected by means of the knife 12, that is to say when the spring plate 11 is pulled by the magnet C₁, the circuit for the magnet C₂ is closed as above mentioned. At the same time another or supplementary 90 electric circuit for the magnet C₁ is closed, which circuit consists of the contact pieces 12 and 14, coils of the magnet C₁, the line 17, contact pieces 9, 10 and 8, the line 18, the batteries B₁, the line 20 and the spring piece 95 11. It is noted that the three circuits above-mentioned include the contact pieces 8, 10 and 9, so that any of the circuits is not closed while the spring handle 1 is not in the running position. It is further noted that the 100

third or supplementary circuit which is closed by the energization of the magnet C_1 includes the coils of the magnet, so that current for the magnet C_1 can pass through either or both of the main and supplementary circuits.

In Fig. 2, 22 is a frame for wire-healds H which are supported on two metallic rods 23 and 23^a. A metallic rod 24 is held on the frame parallel to the rod 23^a keeping a little distance therefrom, and electrically insulated from the frame, but is electrically connected to a rod 25 by means of a cord 26. Rods 25 and 27 are firmly fixed to the frame of healds vertically, and the rod 27 is electrically connected with a side piece 22^a of the frame, but the other rod is insulated from the frame. Each rod provides contact pieces 28 and 29, respectively, and slides up and down together with the frame 22. 30 and 31 are contact pieces which are connected to the lines 15 and 16, respectively. The positions of the pieces 30 and 31 relative to the pieces 28 and 29 are such that when the frame 22 is at the lowest position the pair of contact pieces 28 and 29 are in contact with the pieces 30 and 31 respectively as shown in full lines in Fig. 2, but if the frame is in any other position than the lowest one, the contact pieces 30 and 31 are not bridged and the circuit is not closed.

When the loom is running in good condition, all the wire-healds are pulled upwards by the tension of warp threads when the frame 22 is in the lowest position. If a thread is broken or abnormally slackened, the wire-heald for that thread is not pulled upwards even when the frame is in the lowest position, but drops as shown by Fig. 2, so that the rods 23^a and 24 are electrically connected by the dropped wire-heald, thus an electric circuit is closed when the frame comes to the lowest position, by the rod 25, cord 26, the rod 24, wire-heald H_2 , the rod 23^a, the side piece 22^a of the frame, the rod 27, the pair of contact pieces and the lines 15 and 16.

When the lines 15 and 16 are electrically closed, the electric magnet C_1 is energized, and the spring piece 11 is pulled so as to make a contact of the knife 12 with the pieces 13 and 14. By this contact the supplementary circuit is closed and current for the magnet C_1 can pass through either or both of the main and supplementary currents and so that the contact is made more steady and reliable. At the same time the magnet C_2 is energized and pulls the iron piece 4^b bringing the horizontal spindle 5 in the way of the projection 6 of the slay. At the end of the next stroke of the slay, the projection 6 strikes the horizontal spindle 5, which in turn strikes the spring handle 1, and the latter changes its position breaking all the circuits as shown in dotted lines in Fig. 1,

and the loom's motion is stopped as in the usual way.

In the modification shown in Fig. 4, different batteries B_1 and B_2 are used for the magnets C_1 and C_2 , respectively. The pull of a spring-iron-piece 13^a by the magnet C_1 , closes an independent circuit for the magnet C_2 . This modification is preferably adopted when a high voltage electric current is used for the magnet of a stopping mechanism while a low voltage electric current is used for the relay.

In the other modification shown in Fig. 5, a single magnet is used for both stopping mechanism and relay. In this case an electric circuit for the magnet C_2 in Fig. 1, is of course eliminated.

According to this invention, when the main circuit including wire-healds is closed, the supplementary circuit with a common electric source is established in parallel to the wire-heald, so that if a contact point at the wire-heald is accidentally open due to vibration of the loom, no sparking would be caused at the contact point, otherwise the point would be injured.

Claims:

1. In an automatic stopping system for power looms, the combination with the wire-healds which are pulled upwardly by the tensioning of the warp thread, and a rod arranged in juxtaposition to the healds, the said rod being in the path of downward movement of a dropped one of said healds, the heald frame of the loom including a metallic rod spaced above the first mentioned rod whereby the metallic wire heald, in dropped position, will bridge the two rods, a pair of contacts supported in spaced relation to each other, conductor rods extending upwardly from the heald frame, contacts carried by the conductor rods and engageable with respective ones of the first mentioned contacts, one of said conductor rods being in circuit with the first mentioned rods, the rod of the heald frame being in circuit with a metallic part of said frame constituting also an electrical conductor and the other one of the conductor rods being in circuit with said metallic parts, another pair of spaced contacts, an electro-magnet arranged in juxtaposition thereto, one of said contacts and one terminal of the winding of the magnet being in circuit with one of the first mentioned contacts and likewise with one of the last mentioned contacts, an electro-magnet having one terminal in circuit, with the other one of the second mentioned contacts, the said electro-magnet embodying an armature having means for bridging the second mentioned contacts when the electro-magnet is energized, a second electro-magnet in circuit with the other one of the second mentioned contacts and having an armature pivotally mounted and normally spaced there-

from, a switch including spaced terminals one of which is in circuit with the second mentioned electro-magnet, and one terminal of the magnet the other terminal of the first mentioned electro-magnet being in circuit with the said other terminal of the second mentioned magnet, a source of current supply in circuit with the other one of the bridge contacts and with the other one of the first mentioned contacts, an actuating spring-handle for stopping the motion of the loom, the said spring handle being provided with a conductor element for bridging the bridge contacts when the second mentioned electro-

15 magnet is energized, operative connection between the armature of said magnet and the handle effecting the release of the arm and its movement through its resiliency upon energization of the second mentioned magnet, 20 and another circuit including an electro-magnet, a source of current supply therefore, a switch comprising contacts corresponding to the second mentioned contacts and a bridging means therefore in common, with the 25 bridging means of the armature of the second mentioned electro-magnet, and means, actuated through the movement of the spring handle for stopping motion, to break all of said circuits.

30 2. An automatic stopping system for power looms, comprising a circuit including an electric magnet, a spring-handle, controlling mechanism for said handle, the energization of said magnet effecting actuation of the said 35 controlling mechanism of the spring handle, which latter is for stopping motion, a relay unit which includes an electric magnet and contact pieces for the circuits of the two electric magnets, two electric circuits including a source of current supply, the coils of the relay magnet being common to each circuit, and means for automatically closing one of the circuits through the relay when a warp thread is broken.

40 45 3. An automatic system for power looms, comprising, a circuit including an electric magnet, a spring-handle, controlling mechanism for said handle, the energization of said magnet effecting actuation of the said controlling mechanism of the spring handle, which latter is for stopping motion, the circuit for the magnet including an independent source of current supply, a relay unit including an electric magnet and contact 50 pieces for the circuits of the two electric magnets, two electric circuits including a source of current supply, the coils of the relay being common to each circuit, and means operable to automatically close one of the 55 circuits of the relay when a warp thread is 60 broken.

4. An automatic stopping system for power looms, comprising a circuit including an electromagnet, a spring handle, controlling mechanism for said handle, the energization

of said magnet effecting actuation of the said controlling mechanism of the spring handle, which latter is for stopping motion, an electric circuit including an electromagnet, and a relay which comprises the above mentioned electromagnet and contact pieces, another circuit in which the contact pieces are located and which includes an electric source, and the coils of the electromagnet, common to the aforesaid circuit, and means operating to automatically close the aforesaid circuit when a warp thread is broken.

In testimony whereof I have signed my name to this specification.
